UNITED STATES PATENT OFFICE.

WALTER S. MCLEMORE, OF ESTABUTCHIE, MISSISSIPPI, ASSIGNOR OF ONE-HALF TO ROSS WEDGEWORTH, OF ESTABUTCHIE, MISSISSIPPI.

BALING-PRESS.

SPECIFICATION forming part of Letters Patent No. 693,983, dated February 25, 1902.

Application filed August 9, 1901. Serial No. 71,513. (No model.)

To all whom it may concern:

Be it known that I, WALTER S. MCLEMORE, a citizen of the United States, residing at Estabutchie, State of Mississippi, have invented 5 a new and useful Baling-Press, of which the following is a specification.

My invention is an improved baling-press; and it consists in the peculiar construction and combination of devices hereinafter fully set 10 forth and claimed.

In the accompanying drawings, Figure 1 is a side elevation of a baling-press embodying my improvements. Fig. 2 is a top plan view of the same, the sweep-lever being omitted. 15 Fig. 3 is a vertical longitudinal central sectional view of my improved press, the follower being shown in elevation. Fig. 4 is a horizontal sectional view of the same. Fig. 5 is a detail perspective view of the follower.

20 The press-box 1 is horizontally disposed and comprises the ground frame 2, the upper frame 3, the bottom 4, the top 5, and the sides 6. The top and bottom frames are connected together by suitable studs 7, which are on the 25 outer sides of the sides 6, at the ends thereof, as shown. The opposite ends of the press-box are open and the same are provided with doors 8, which are hinged at their lower sides to the frame 2, as at 9, and are adapted to close the 30 ends of the press-box. I provide suitable bars 10 to lock the doors 8 when closed. As here shown, each bar 10 is hingedly connected at one end to a support 11 and at its free end is adapted to be engaged with a locking - de- 35 tent 12.

Blocks 13 are connected in pairs, one above the other, to the studs 7, and between the said pairs of blocks at the ends of the sides of the press-box are mounted direction-sheaves 14. 40 On opposite sides of the press-box, at the center thereof, are drums 15, which are vertically disposed and are carried by vertical shafts 16, which are journaled in bearings 17, with which the frames 2 3 are provided. At the 45 upper end of each drum-shaft is fixed a spur-wheel 18. A vertical shaft 19 is journaled in bearings 20 on the upper side of the press-box, at the center of the same. To the said shaft is fixed a gear-wheel 21, which engages the 50 gears 18 and is disposed midway between them, as shown in Fig. 2. At the upper end

of the shaft 19 is a socket or keeper 22, to which may be attached the inner end of a suitable sweep-lever 23, whereby the shaft 19, with its gear 21, may be rotated in either direction in order to rotate the drums 15. 55

In the press-box is a follower 24, which may be of any suitable construction, is double-faced, as at 25, at its ends, and is provided with a central opening 26, which is here shown 60 as in a centrally-disposed block or stud 27, which connects the upper and lower sides of the follower. In the sides 6 of the press-box are longitudinal open-ended slots 28, through which baling-wires may be passed around the 65 bales formed in opposite ends of the press-box, and the said sides 6 are further provided with slots 29.

A suitable flexible connecting element, here shown as a rope 30, is partly coiled in reverse 70 directions on the drums 15, is passed around the direction-sheaves 14 and through the central opening 26 in the follower, and through the slots 29.

When the sweep-lever 23 is turned in one 75 direction, the follower will be moved toward one end of the press-box, and when the rotation of the sweep-lever is reversed the follower will be moved in the opposite direction toward the other end of the press-box, as will 80 be understood, the drums which are rotated by the gears hereinbefore described acting on the rope or flexible connecting element in such manner as to thus operate the follower.

The hay or other material to be baled may 85 be placed in the press-box at opposite ends thereof by means of the doors 8, and the latter when closed coact with the follower in compressing the hay to form bales in the ends 90 of the press-box. It will be understood that while hay is being placed in one end of the press-box the press may be in operation to form a bale in the opposite end of the press-box, and hence the capacity of the press is doubled, as will be understood. 95

Having thus described my invention, I claim—

In a baling-press, a press-box having its opposite ends open and provided with suitable closures, said press-box being further provided with longitudinal slots in its sides and direction-sheaves at its ends, in line with 100

said slots, in combination with a follower in the press-box, adapted to be moved in either direction therein and having a central transverse opening, winding-drums on opposite 5 sides of and without the press-box, out of the path of the follower and intermediate the ends of the press-box, means to simultaneously rotate said drums in either direction and a flexible connecting element secured to 10 and partly coiled in reverse directions on said respective drums, and having bights engag-

ing said direction-sheaves, disposed in said slots and rove through the central opening in the follower, substantially as described.

In testimony that I claim the foregoing as 15 my own I have hereto affixed my signature in the presence of two witnesses.

WALTER S. MCLEMORE.
